UNITED STATES PATENT OFFICE.

ROBERT J. M. DANLEY, OF BROOKLYN, AND LOUIS A. SNYDER, OF NEW YORK, N. Y.

FOLDING-MACHINE.

1,293,357.

Specification of Letters Patent.

Patented Feb. 4, 1919.

Application filed April 19, 1918. Serial No. 229,531.

To all whom it may concern:

Be it known that we, ROBERT J. M. DANLEY and LOUIS A. SNYDER, both citizens of the United States, said DANLEY residing in Brooklyn borough, county of Kings, city and State of New York, and said SNYDER residing in New York city, county of New York, and State of New York, have invented certain new and useful Improvements in 10 Folding-Machines, of which the following is a specification.

This invention relates to means for doubling or longitudinally folding a web of paper, which is usually previously printed, 15 and also usually provided with longitudinal rows of perforations along the lines where the web is to be folded or doubled and redoubled upon itself in zigzag or fan-fold form.

20 One of the principal objects of the invention is to produce a simple, inexpensive and effective means for drawing the web over and through the devices which gather it into a doubled or fan-folded condition.

25 Upon paying off from the roll, the web is duly led over a turning bar which has a special form, to facilitate the gathering of the web. Between said bar and a final former are employed web-gathering guide fingers, which protrude in opposite directions against the opposite sides of the web, and aid to form longitudinal gathers or grooves therein at the proper points, so that 30 said fingers coöperate with the final former or guide and with said special bar, to reduce the web to a gathered or fan-folded condition.

Below said final former or guide, there is 35 provided a work-feeding device which draws the web up as it leaves the supply roll, and pulls it first over an upper guide and over said special bar, and then down past the grooving or gathering fingers, and then through the final former. This feeding device is in the form of a pair of coöperating 40 endless chains which are placed one upon each side of the web, each chain being provided with a series of projecting rubber grips or clips, the grips upon one chain being paired with those upon the other chain, and the grips coöperating to pinch the folded web between them. This chain feed is disposed in the middle of the work or product, to engage the same along a single 45 vertical line, whereby liability of irregular feeding of the web and consequent difficulty

is avoided. Below the feeding chains the web may be delivered to a tray or other receptacle, or may be otherwise disposed of.

Other features and advantages will here- 60 inafter appear.

In the accompanying drawings,

Figure 1 is a side elevation of an apparatus embodying the present improvements, showing the original web as paying off from the supply-roll and finally gathered into a 65 fan-folded product.

Fig. 2 is a rear elevation of the machine, illustrating the gathering, folding and delivery of the web.

70 Fig. 3 is an enlarged sectional rear elevation, taken about centrally of the machine, illustrating details of the web-feeding mechanism.

Fig. 4 is an enlarged side elevation of the 75 feeding devices, etc.

Fig. 5 is a diagram to show the web in a fluted or partly gathered condition as it feeds past the gathering fingers 19.

Fig. 6 is a diagram to show the web at 80 a later stage as it passes by the guide-fingers 29, just previous to entering the final former.

The web is usually received from the printing press in the form of a roll 10, and is usually provided with continuous longitudinal rows of perforations 11 along the lines upon which the web is to be doubled or folded. From the roll the web may be paid off or loosened, and then led upwardly to an elevated horizontal guide bar or roll 85 11^a, over which it turns to travel horizontally to about the middle of the machine, where it turns over a second bar 12 and vertically descends. This second bar 12 is arched or bowed upwardly, as shown, to 90 facilitate the gathering of the web into a multiple-fold product. The curve of the bar may be struck from about the point of convergence 13 of the folds, as at Fig. 2.

95 This guide arch is mounted for adjustment to bring it exactly to the position of greatest efficiency for different classes of work, as required. For the purpose of adjustment, the arch may be provided with arms 14, whereby it is mounted on pintles 100 or pivots 15 at the sides of the upper framework; said pintles mounted in brackets 16 fixed upon rods 17 forming parts of the general framework. It will be seen that either side of the arch may be swung horizontally 110 a trifle, in order to bring the arch into true position; or that the arch may be swung

broadside either forwardly or backwardly, as required, and in either case secured by means of nuts 18. This arch is preferably mounted so that its delivery face is in a vertical plane which intersects the middle of the folded product at the lower or delivery part of the apparatus.

From this arch the path of the web descends between opposite overlapping guides or gatherers in the form of fingers 19, which are arranged alternately upon opposite sides of the gathering web and guide it into a fluted condition (Fig. 5) at a point about midway between the overlying arch 12 and an underlying guide 20 which brings the web into its final fan-folded or doubled condition, said guide 20 being arranged directly under the arch 12, and in position to coöperate properly with the row of fluting fingers 19. Said fingers are in the form of fixed rods projecting inwardly from split blocks 21 which are adjustable along supporting rods 22 fixed in opposite sides of the framework; and said framework may comprise standards 23 rising from a base 24 and having suitable members to support the rods and other devices herein specified.

The final former or gatherer is in the form of a block 20, having a central, vertical slot or hole 25, oblong in cross-section, by which the web is brought to its final fan-folded condition; the upper part of this hole having its side edges rounded at 26 to facilitate the final closing of the web plies together to complete the fold. This block or former is mounted on suitable supports or uprights 27 fixed upon the framework of the machine, and may be replaced by a block having a different dimension of hole, to suit either a narrower or a wider product, screws or other fastening devices 28 securing the block to the supports.

Just above the former 20 is provided a second series of overlapping, oppositely-projecting guides in the form of horizontal fingers 29, Figs. 1 and 2, to lie within the folds of the nearly folded web, and aid in finishing the fold and guiding the web to the final former 20. These guide fingers 29 may be parallel round rods mounted upon opposite brackets 30, the free end of each rod projecting toward the opposite bracket, so that the fingers may enter the alternate folds in the web; and there being one finger for each fold. These rods may be spaced apart as required, and clamped upon the brackets by means of overlying bars 31, at the ends of which are arranged clamping bolts 32; the bars 31 being preferably faced with felt, as at 33; and a similar facing being provided upon the top surface of the bracket 30, so as to hold the fingers securely.

The final forming block 20 is made adjustable edgewise (by means of slots 33^a) to facilitate making corrections in the path

of the web. By means of the independent adjustment of the arch 12 and of the final forming block 20 (as well as of the guides 29), the web can be brought under accurate control, even if the parts of the apparatus are crudely constructed.

Below the former 20, and arranged about centrally thereof and on the central line of the machine, is a two-part feeder, comprising on each side of the folded web a single endless chain 34 provided with frictional clips or feeding blocks 35, these blocks being usually of soft rubber. The chains are co-operative and may be duplicates, one upon one side of the web-product 36 and one upon the other side, and the feeding blocks are paired upon the opposite chains, so that the blocks in each pair may coöperate to clip the web-product firmly between them and pull the same down.

The chains run over pairs of upper and lower sprocket wheels 37, 38, which are mounted upon shafts 39, 40, the latter connected by similar gears 41, 42; and a motor 43 may be employed to drive the system of web-feeding chains; said motor being suitably connected to one of the sprocket shafts 39 or 40.

The rubber clip-blocks 35 are arranged at intervals upon each chain to agree with the arrangement of the blocks upon the other chain, and come opposite to each other to clip the paper, as seen at Fig. 3. These clips are at such frequent intervals upon the chain that the web is always in control, and always being pulled down by at least one pair of clips, so that the pull upon the web is continuous. The pull as illustrated is a single central or midway pull upon the product, whereby liability of skewing, distortion or injury of the product is minimized or avoided, a good speed of operation is made practicable, and a reliable feed of the web over and through the various guides is assured.

A substantial advantage is gained in providing, for the purpose of advancing the web, a pulling device which acts upon the product along a single line centrally thereof. It is found in practice that by means of this device liability of misfeeding of the web is minimized or avoided, and accurate construction of parts is rendered unnecessary, since the central draft upon the web tends to be self-corrective, thereby minimizing or overcoming any liability of the web to creep from side to side, or otherwise act in a faulty manner.

From the feeding chain the product may descend into any suitable receptacle or other device, as may be desired.

It will be understood that any former 20 will be centrally placed with reference to the double feeding chain, so that said chain will serve its purpose efficiently in drawing through the machine all fan-folded products

of various widths. Various sizes of formers 20 may be used from time to time as required.

Each rubber block 35 may be secured by 5 means of a pair of jaws or clips 44, which may converge outwardly from a link of the chain; the yielding rubber being sprung into place between said jaws so as to be securely retained thereby.

10 The inner reaches of the feeding chains may be suitably backed or supported, so as to enable the rubber blocks to grip the web-product firmly between them. One method of supporting the chains at these points is 15 illustrated in the drawings, in which horizontal rollers 45, placed near together, one above another, are used to back the chains. These supporting rollers may be either mounted upon pivots 46 or they may lie 20 loosely one upon another in a frame 47. In either case, they support firmly the links of the chain which bear the rubber clips. In some cases, the rollers 45 may be omitted, and the chain links may bear directly against 25 the back portion of the frame 47, which, in that case, would be contiguous to the links.

By mounting the arched guide 12 in a plane which is about parallel with the general direction of downward travel of the web 30 from said arch, the gathering of the web is greatly facilitated, and a further advantage is gained by adjusting said arch upon the pivots 15, to bring the same into proper relationship to the gathering and folding devices arranged under said arch.

Variations may be resorted to within the scope of the invention, and portions of the improvements may be used without others.

Having thus described our invention, we 40 claim:

1. The combination of an arched guide at the introductory side of the machine over which the web is led, a final former for the gathered web, and a series of overlapping 45 oppositely-projecting guides between said former and said arched guide, the latter mounted in a plane which intersects the middle of the folded product at the final former.

50 2. The combination of an arched guide at the introductory side of the machine over which the web is led, a final former for the gathered web, a series of overlapping oppositely-projecting guides between said former and said arched guide, the latter mounted in a plane which intersects the middle of the folded product at the final former, and means for effecting adjustment of said arched guide.

60 3. In an apparatus for gathering a web into fan-fold form, the combination of a final former, guides in advance of said final former over which the web is led and gathered, and a feeding device at the delivery side of said final former for drawing the

70 web through the apparatus, said feeding device comprising devices upon opposite sides of the product to grip and advance the same, said gripping devices in the form of endless chains, each having means to engage the web.

4. In an apparatus for gathering a web into fan-fold form, the combination of a final former, guides in advance of said final former over which the web is led and gathered, a feeding device at the delivery side of said final former for drawing the web through the apparatus, said feeding device comprising devices upon opposite sides of the product to grip and advance the same, 75 said gripping devices in the form of endless chains, each having means to engage the web, said web-engaging means being disposed about at the center line of the product, and means to drive said chains.

5. In an apparatus for gathering a web into fan-fold form, the combination of a final former, gathering devices in advance of said final former, and feeding chains on the delivery side of said final former, said chains 80 mounted one upon each side of the product, to work in a plane which is about midway between the side edges of said final former, to exert a central draft upon the product.

6. The combination of an arched guide at the introductory side of the machine over which the web is led, a final former for the gathered web, and a series of overlapping oppositely-projecting guides between said former and said arched guide, the latter 95 mounted in a plane which intersects the middle of the folded product at the final former, the curve of said arched guide being struck from about the point of final convergence of the folds.

7. In an apparatus for gathering a web into fan-fold form, the combination of a final former, gathering devices in advance of said final former, coöperative feeding chains on the delivery side of said final former, said chains mounted upon each side of the product, and means for supporting the links of the chains along those reaches which are adjacent to the product to enable 100 the chains to grip the product.

8. In an apparatus for gathering a web into fan-fold form, the combination of a final former, gathering devices in advance of said final former, coöperative feeding chains on the delivery side of said final former, said chains mounted upon each side of the product, and means for supporting the links of the chains along those reaches which are adjacent to the product to enable 110 the chains to grip the product, said supporting means in the form of a series of rolls over which the links of the chains run.

9. The combination with web-gathering devices including a final former, of a feeding device on the delivery side of said final 115

- former to engage the product, said feeding device in the form of a pair of coöperating endless chains placed one upon each side of the product, and means to drive said chains.
- 5 10. The combination with web-gathering devices including a final former, of a feeding device on the delivery side of said final former to engage the product, said feeding device in the form of a pair of coöperating endless chains placed one upon each side of the product, and means to drive said chains; each chain being provided with a series of projecting rubber grips, the grips upon one chain being paired with those upon the 15 other chain to pinch the product between them.
- 10 11. The combination with web-gathering devices including a final former, of a feeding device on the delivery side of said final former to engage the product, said feeding device in the form of a pair of coöperating endless chains placed one upon each side of the product, and means to drive said chains; each chain being provided with a series of 20 projecting rubber grips, the grips upon one chain being paired with those upon the other chain to pinch the product between them, said chains being disposed along the middle line of the product to give a central draft thereto.
- 20 12. The combination of an arched guide at the introductory side of the machine over which the web is led, a final former for the gathered web, a series of overlapping oppositely-projecting guides between said former and said arched guide, the latter mounted in a plane which intersects the middle of the folded product at the final former, and means whereby said arched guide is mounted to afford adjustment of one end independently of the other.
- 25 13. The combination of an arched guide at the introductory side of the machine over which the web is led, a final former for the gathered web, and a series of overlapping oppositely-projecting guides between said former and said arched guide, the latter mounted in a plane which intersects the middle of the folded product at the final former, 30 said arched guide being hinged at its ends to afford a swinging adjustment of the arch.
- 30 14. The combination of an arched guide at the introductory side of the machine over which the web is led, a final former for the gathered web, and a series of overlapping oppositely-projecting guides between said former and said arched guide, the latter mounted in a plane which intersects the middle of the folded product at the final
- former, each of said arched guide and final 60 former being adjustable relatively to the other.
15. The combination with web-gathering devices including a former, of a two-part feeder arranged upon the central line of the 65 folded web, said feeder comprising on each side of the folded web a single endless chain, provided with frictional clips.
16. The combination with web-gathering devices including a former, of a two-part 70 feeder arranged upon the central line of the folded web, said feeder comprising on each side of the folded web a single endless chain, provided with frictional clips, the clips upon one chain being paired with those upon the 75 other.
17. The combination with web-gathering devices including a former, of a two-part feeder arranged upon the central line of the 80 folded web, said feeder comprising on each side of the folded web a single endless chain, provided with frictional clips, the clips upon one chain being paired with those upon the other, upper and lower sprocket-wheels for each chain, gearing connecting said sprocket-wheels, and means to drive the feeder.
18. The combination with web-gathering devices including a former, of a two-part feeder arranged upon the central line of the 85 folded web, said feeder comprising on each side of the folded web a single endless chain, provided with frictional clips, the clips upon one chain being paired with those upon the other, said clips being at such frequent intervals upon the chains that the web is always in control of said feeder and always being advanced by at least one pair of clips.
19. The combination with web-gathering devices including a final former, of means 90 on the delivery side of said final former for imparting to the web a continuous pull; said feeding means arranged along the central line of the product.
20. The combination with web-gathering 105 devices including a former, of a two-part feeder arranged upon the central line of the folded web, said feeder comprising on each side of the folded web a single endless chain, each of said chains having at intervals links 110 provided with jaws or clips, and yielding frictional feeding blocks gripped by said jaws.
